PLURAL COMPARTMENT PRESSURIZED DISPENSING CONTAINER

Norman Howard Kemp, 8585 N. Stemmons-Freeway,
Suite 931, Dallas, Tex. 75247

Filed July 13, 1973, Ser. No. 378,811

Term of patent 14 years

Int. Cl. D9—01

U.S. Cl. D9—18

FIG. 1 is an exploded, top front perspective view of a plural compartmented pressurized dispensing container showing my new design; and

FIG. 2 is an exploded, bottom rear perspective view thereof.

I claim:

The ornamental design for a plural compartment pressurized dispensing container, substantially as shown.
